CLAIM

The ornamental design for a cylindrical golf ball display, as shown and described.

DESCRIPTION

FIG. 1 is a front elevation view of my new design for a cylindrical golf ball display;

FIG. 2 is a right side elevation view of my new design for a cylindrical golf ball display;

FIG. 3 is a left side elevation view of my new design for a cylindrical golf ball display;

FIG. 4 is a rear elevation view of new design for a cylindrical golf ball display;

FIG. 5 is a top plan view of my new design for a cylindrical golf ball display;

FIG. 6 is a bottom plan view of my new design for a cylindrical golf ball display; and,

FIG. 7 is a top perspective view of my new design for a cylindrical golf ball display.

The broken lines indicating golf balls in FIGS. 1, 2, 3, 4 and indicating bottom features in FIG. 6 are for the purposes of illustration only and form no part of the claimed design.
